A. B. GULLY

VALVE GRINDER

Filed Feb. 16, 1923

Inventor

Albert B. Gully

By Chamberlain & Neumann
Attorneys

UNITED STATES PATENT OFFICE.

ALBERT B. GULLY, OF STRATFORD, CONNECTICUT.

VALVE GRINDER.

Application filed February 16, 1923. Serial No. 619,390.

To all whom it may concern:

Be it known that ALBERT B. GULLY, a citizen of the United States, and resident of Stratford, in the county of Fairfield and 5 State of Connecticut, has invented certain new and useful Improvements in Valve Grinders, of which the following is a specification.

The present invention relates to an improved valve grinding tool, particularly for grinding the valve of internal combustion engines.

An object of the invention is to provide a manually operated device of this character, which may be operated by comparatively unskilled persons, in a manner to efficiently and uniformly grind valves. A further object is to provide such a device by which either of the well known types of 20 valves, provided in one case with diametrically opposed holes, and in the other case with a transverse slot, may be ground without removal or substitution of any parts.

A still further object is to enable the 25 grinding to be carried out with the tool in a non-vertical position, when desired; this being desirable where the structure of the engine may prevent the grinding tool being held vertically.

With the above and other objects in view, 30 an embodiment of the invention is shown in the accompanying drawings, and this embodiment will be hereinafter more fully described with reference thereto, and the invention will be finally pointed out in the claims.

In the drawings:

Fig. 1 is an elevation of the complete device, showing the same engaged with one 40 type of valve, the device being shown in one position of operation;

Fig. 2 is a similar view showing the device in another position of operation;

Fig. 3 is a transverse sectional view taken 45 on the line 3-3 of Fig. 1; and

Fig. 4 is a fragmentary view showing the device engaged with another type of valve.

Similar reference characters indicate corresponding parts throughout the several figures of the drawings.

Referring to the drawings, the embodiment of the invention shown therein, comprises a cylindrical shaft or rod 10, having its upper end rotatably engaged to oscillate

in the cylindrical passage 11 of a fixed 55 member 12, extending laterally at each side of the rod and having slots 13 and 14 cut therein. Within these slots there are pivotally mounted upon screw pivots 15 and 16 a pair of scissor-action levers 17 and 18, the 60 lower arms of which extend at each side of the rod, in substantially parallel relation therewith in their contracted position, while the upper arms are bent outwardly from each other, and are shaped so as to be conveniently gripped by the hand.

A coil spring 19 surrounds the rod just below the member 12, the lower end being carried through and fixed in a hole 20 of the rod, while the upper end is carried beneath 70 and held by the nut on the pivot screw 15.

The lower ends of the levers are provided with grooves 21 and 22, respectively, and apertures 23 and 24, and have secured thereto the ends of a flexible cord element 25, 75 which may be formed of raw-hide, leather, hemp or other suitable material. The ends are fastened by passing them through the apertures and running them beneath a loop disposed in the grooves. The intermediate 80 portion of the cord is passed through a hole 26 drilled transversely through the rod, the two reaches extending from the ends of the hole being wound about the rod in the same direction, the spring 19 being adapted to 85 yieldingly maintain the rod in a position to wind the cord thereabout, and to contract the lower arms of the levers, as indicated in Fig. 1.

A pair of bosses or projections 27 and 28 90 upon the inner sides of the levers hold them in spaced relation to the rod, so that they will not engage the spring 19 and the cord coiled about the rod.

At its lower end the rod is provided with 95 a slot 29 forming a forked structure, and within which slot there is rotatably mounted, upon a fixed pivot pin 30, a blade element 31, adapted for engagement with the valve. Most valves are of either of the two types, 100 respectively provided with diametrically opposed holes 32 and 33, as indicated in Fig. 1, and with a transverse slot 34, having a centering recess 35, as indicated in Fig. 4. For the purpose of engaging either of these types, the blade is provided along one side 105 with a pair of spurs or prongs 36 and 37 adapted to be engaged with the holes 32

and 33 of the type of valve shown in Fig. 1, and along another side with a straight edge 38 having a center projection or spur 39, adapted to be engaged with the slot 34 of the type of valve shown in Fig. 4. The slot 29 is of such depth that the blade may be freely rotated therein to bring either of the valve engaging portions into position. The pivotal mounting of the blade is also in the nature of a universal joint, permitting the valve to be oscillated with the rod 10 at an angle, as indicated in dotted lines in Figs. 1 and 2.

In operation, the blade is engaged with the valve, and the upper handle ends of the levers 17 and 18 are gripped in the hand of the operator, as shown in Fig. 1. He thereupon brings the handle ends together, with a squeezing motion as shown in Fig. 2, the uncoiling of the cord 25 oscillating the rod 10 in one direction, and tensioning the spring 19. Upon release of the lever the spring 19 oscillates the rod 10 in the other direction bringing the levers again to their position as shown in Fig. 1. This scissor-like operation is continued, the valve after each grinding operation being preferably turned in its seat slightly, by bodily turning the tool.

I have illustrated a preferred and satisfactory embodiment of the invention, but it is obvious that changes may be made therein, within the spirit and scope thereof, as defined in the appended claims.

Having thus described my invention, what

I claim and desire to secure by Letters Patent is:

1. In a valve grinding implement, an oscillating rod, a valve engaging element at one end of said rod, an integral fixed member journaling the other end of said rod, a pair of levers pivotally mounted on said fixed member at each side of said rod, a spring coiled about said rod having one end connected thereto and its other end connected to one of the pivots in said fixed member to which said levers are pivoted, and a cord connected at its ends to said levers and coiled about said rod.

2. In a valve grinding implement, an oscillating rod, a valve engaging element at one end of said rod, means for oscillating said rod comprising a pair of levers pivotally mounted at each side of said rod and a spring coiled about said rod having one end connected thereto and its other end connected to one of the pivots in a fixed member to which said levers are pivoted and a flexible cord connected at its ends to said levers and coiled about said rod, and projections on said levers adapted to engage the rod to space the levers from the cord coiled on the rod.

Signed at Bridgeport, in the county of Fairfield and State of Connecticut, this 15th day of February A. D., 1923.

ALBERT B. GULLY.
